UNITED STATES PATENT OFFICE.

DAVID A. RITCHIE, OF CAMBRIDGEPORT, MASSACHUSETTS.

MACHINE FOR MAKING METAL TUBING.

SPECIFICATION forming part of Letters Patent No. 349,748, dated September 28, 1886.

Application filed February 6, 1886. Serial No. 191,063. (No model.)

To all whom it may concern:

Be it known that I, DAVID A. RITCHIE, of Cambridgeport, county of Middlesex, and State of Massachusetts, have invented an Improvement in Machines for Making Metal Tubing, of which the following description, in connection with the accompanying drawings, is a specification, like letters on the drawings representing like parts.

10 This invention has for its object to provide means whereby a sheet-metal pipe made from a folded strip may be corrugated longitudinally.

This invention is an improvement on the class of machines represented in United States Patent No. 161,134, granted to me October 27, 1885; and my invention consists, essentially, in the combination, with a mandrel over which the tube is formed, of a corrugated horn and a surrounding series of corrugators to act upon 20 the outside of and press the said pipe into the grooves of the horn, as will be described.

Figure 1, in longitudinal section, represents a mechanism which, taken in connection with the mechanism described in my said patent, 25 will enable my invention to be readily understood, and Fig. 2 is a left-hand end view of the corrugating devices, and the said figure showing an end view of the mandrel, which in cross-section is the same as the cross-section of 30 the pipe which will be drawn thereover.

Referring to the drawings, the mandrel C, the co-operating pairs of pulling-rolls h^1 , h^2 , n^1 , n^2 , and m^1 , m^2 , the finger g , which bends down the usual flanged edges of the strip from which 35 the pipe is made, after the flanged edges thereof are interlocked, the stand g' , to hold the finger, the flange-bending device p' on the shaft p^2 , and the extension r are all substantially as in my said patent, wherein the said parts are 40 designated by like letters, a completed pipe made from a strip being delivered from the delivery end of the mandrel. To the delivery end of the mandrel I have attached a solid horn or beak, B, it being, as herein shown, 45 screwed into the screw-threaded interior portion of the mandrel. This horn or beak B, substantially cylindrical at its junction with the mandrel, is beyond that point provided with a series of longitudinal grooves, which 50 preferably gradually increase in depth for some distance beyond the end of the mandrel. Surrounding the horn or beak is an annular

head, B', supported upon the foot B². The annular head is extended forward to form a hub, b, and the head carries a series of ears, b', to which are pivoted by pivots b² a series of corrugators, c, made preferably as arms, each arm preferably having in it an anti-friction roller, c', each arm or corrugator being acted upon by a pressure-regulating device, e, herein shown as a screw, the said screw causing the acting faces of the corrugators resting upon the sheet-metal pipe or tube passing between them and the beak or horn, and depressing the surface of the said pipe into the longitudinal 65 spaces or grooves made in the periphery of the beak or horn. As the result of this construction, a circular pipe delivered from the mandrel upon the beak or horn will be delivered from the latter longitudinally corrugated, substantially as shown in Fig. 2, the 70 number of corrugations and their depth depending upon the number of longitudinal grooves made in the beak or horn and upon the number of corrugators or arms c which are 75 arranged outside the tube or pipe.

I claim—

1. A mandrel to receive a sheet-metal pipe, combined with a longitudinally-corrugated beak or horn and with a series of corrugators, 80 to operate substantially as described.

2. The mandrel and its attached longitudinally-corrugated beak or horn and the head and the series of corrugators arranged about the periphery of the said beak or horn, combined with the series of pressure-regulating devices to regulate the pressure of the corrugators upon the pipe supported by the said horn or beak, substantially as described. 85

3. A mandrel to receive or have formed upon it a pipe, and rollers to act upon the said pipe both externally and internally, combined with the longitudinally-corrugated beak or horn and a series of corrugators arranged about the said beak or horn, to operate substantially 90 as described.

In testimony whereof I have signed my name to this specification in the presence of two subscribing witnesses.

DAVID A. RITCHIE.
